(57) **CLAIM**

The ornamental design for a stroller embellishment kit, as shown and described.

DESCRIPTION

FIG. 1 is a perspective front view of a stroller embellishment kit;

FIG. 2 is a front elevation view of the stroller embellishment kit;

FIG. 3 is a rear elevation view of the stroller embellishment kit;

FIG. 4 is a left side elevation view of the stroller embellishment kit; the right side view being a mirror image thereof;

FIG. 5 is a top plan view of the stroller embellishment kit;

FIG. 6 is a bottom plan view of the stroller embellishment kit; and,

FIG. 7 is a plan view of the components of the stroller embellishment kit.

The broken lines shown represent unclaimed subject matter and form no part of claimed design.
